UNITED STATES PATENT OFFICE.

WILLIAM CORWIN RICKETTS, OF DAYTON, OHIO.

REINFORCED-CONCRETE AND MASONRY STRUCTURE.

1,128,514.

Specification of Letters Patent. Patented Feb. 16, 1915.

Application filed August 4, 1913. Serial No. 782,877.

To all whom it may concern:

Be it known that I, WILLIAM CORWIN RICKETTS, of the city of Dayton, county of Montgomery, State of Ohio, United States of America, construction engineer, having invented certain new and useful Improvements in Reinforced-Concrete and Masonry Construction, do hereby declare that the following is a clear, full, and exact description of the said invention, reference being had to the accompanying drawings, in which—

Figure 1, an isometric view of the Z unit invented and is used throughout this construction. Fig. 2, an isometric view of the method of bonding this unit in the wall. Fig. 3, an isometric view of an unfinished wall showing vertical and horizontal reinforcements in place. Fig. 4, a plan view of a wall of triple thickness, for heavy construction having a reinforced concrete center and hollow outside courses. Fig. 5, is a vertical section of a triple thickness wall with reinforced concrete center in combination with a concrete floor. Fig. 6, an isometric view of a fragmentary portion of a combined reinforced concrete hollow tile floor and reinforced concrete columns in a hollow wall, constructed entirely of Z tile. Fig. 7, a vertical cross section at the intersection of a continuous floor and a supporting wall. Fig. 8, a section of the floor in Fig. 6 with a cement top. Fig. 9, a section of the floor in Fig. 6 with a wood floor top. My invention relates to buildings or structures of masonry in combination with reinforced concrete, and the object of my several inventions is to produce a reinforced concrete structure within a masonry structure, without the use of forms, and with a minimum of material and labor.

Similar letters refer to similar parts throughout the several views.

In the practical application of my invention, I vary the amount of reinforcement steel, and the size and number of reinforcements in the different members through the structure as strength demands.

The unit used throughout my several inventions and upon which the entire system is based is one of my inventions, and is shown in Fig. 1, being of substantially Z shape, and made of cast concrete, and is called such in the following description and claims. Faces A and B being equal in their several dimensions, parallel, and ex-

tending in opposite directions from a cross web or connecting member C, portion A and B being at right angles with respect to C, C having a niche D in the bottom portion which forms an open passage between 60 cells.

By referring to Fig. 2, it will be seen that units 1, 2 and 3 form hollow cells and these three units are bonded together by the 4th unit in the course above, by inverting the same. The cross web of unit 4 coincides with that of unit 2, thus the cross webs of units in a course coincide with those of units in adjacent courses, forming vertical parallel cells E in the wall, said cells having connecting passages through the niches in the cross webs of units in the wall. By referring to Fig. 3, it will be readily seen how the Z tile lends itself to this substantial means of bonding units together to form a continuous hollow wall, and how the niche in the bottom of the web portion gives horizontal air circulation from cell to cell in hollow wall work, as well as, providing admittance for horizontal reinforcements in reinforced concrete work. In practice, on walls that are to be reinforced with these rods G, the mason lays the rods in place before the next course is laid, the niche in the tile permitting the mason to lay his next course without interference from the rods. The vertical rods H shown in Fig. 3 are the vertical reinforcements that I use for columns made of concrete cast in the cells F, and are tied to the horizontal rods G with wire as the wall goes up. The vertical rods are generally in place as the work progresses, and since the Z tile are virtually halves of a whole unit forming a cell, they are readily put in place around this network of rods. The reinforced cells F of Fig. 3, are then filled with concrete forming columns in the wall, cells E remaining hollow; the number of cells 100 reinforced is according to the required lateral stability and also the supporting power of the wall. The number of horizontal reinforcements, and their position in the wall, depends upon the amount of tension strain 105 in the wall and the location of the strain.

By referring to Fig. 4, I show a plan view of my reinforced hollow wall of triple thickness having three rows of tile in a course, the center course carrying the concrete and steel reinforcements as shown in Fig. 3, the outside courses K and J being

hollow. This construction I employ where great lateral strength is required, and insulation from heat or cold is a factor, as would be required in cold storage buildings. Here it will be seen that the Z-tile in row 5 I are inverted with respect to those in rows K and J and interlock therewith. This construction only gives a single thickness of tile between any two cells, which is not only a saving of material but a perfect 10 means of eliminating open joints between cells, which is a vital feature in successful cold storage work. By referring to Fig. 5, a modified section of this triple thickness wall is shown in combination with a reinforced concrete floor L, where the vertical reinforcements H extend laterally into the floor, thus increasing the vertical shear resistance at the point of support of the floor, 15 also tying the wall and floor together and forming a cantaliver support for the floor with the wall and vice versa.

By referring to Fig. 6, another view of the combination of wall and floor work is shown; here the vertical column rods H extend laterally into the floor, and I have utilized the Z-tile to produce a hollow light weight floor. The tile are laid in parallel rows, and so spaced as to form channels between them, in which concrete beams N are cast. The width of the beams varies with the required strength of the floor. The 20 reinforcements H extend laterally from their vertical cells in the wall into these channels, the reinforcements M which are the tension rods of the said ribs are also placed in these channels. Thus the column and floor beams are cast integral as in concrete skeleton structural work, but without 25 the use of forms. I employ a metal fabric R for the bottom slab of this floor construction thus providing means for plastering the ceiling and closing the bottom of the cells P. The niche D provides air communication between cells, which is necessary 30 for the deadening of the sound waves in the floor. If the floor structure is to have a concrete slab top I use a metal fabric S between the slab and the floor structure, 35 it serving as reinforcement as well as means for bridging the cells P, as is shown by Fig. 8. A wooden floor can be placed on the top slab, or it can be laid directly on the floor structure as is shown in Fig. 9. 40 Referring again to Fig. 6, it will be seen that a light metal plaster lath T is laid on the wall between courses 3 and 4, and covering the top of the vertical cells in the wall which are to remain hollow, and also to 45 form a base for the cells to be cast solid above it in course 4. Thus the rod G in course 4 becomes embedded in the concrete forming a reinforced concrete beam. Likewise course 2, 3 and 4 could be cast as one 50 beam to carry the floor load over an open

ing below by placing the metal fabric between courses 1 and 2. Thereby the horizontal rod G in course 2 would act in tension to carry the load as a beam. This method of reinforcing certain courses is 55 also very convenient in carrying the wall over doors and windows.

Fig. 7, shows how I place the vertical reinforcing rods H in a wall supporting a continuous floor. Here rods H will be seen 70 to extend laterally in both directions into the floor, thereby giving rigid strength and stability to the structure.

It is readily seen therefore, that a masonry structure built of Z-tile units in the 80 manner herein described, can have beams and columns of reinforced concrete cast in the wall and integral with the concrete floor, all resulting in a monolithic structure of masonry units and reinforced concrete, 85 while the columns are of small dimensions, yet they are numerous and by this multiple column and multiple floor beam system the combined strength can be made as great as is desired. By this system, the concrete 90 forms are eliminated for all wall work, and only a temporary flat centering is required for floor work.

It is obvious that I may employ one or 95 more reinforcing rods side by side in a single floor reinforced member for strength or convenience, and likewise in the vertical columns.

Having thus described my invention what I claim is—

1. A reinforced concrete and masonry structure, the combination of walls built of Z shape structural tile with the cross webs of each unit coinciding with those of units in succeeding courses forming vertical parallel cells in the wall, a niche in the top of said cross webs, horizontal steel rod reinforcements through said niches, and vertical concrete columns cast in said vertical cells, reinforced concrete floors supported by said walls and columns, and vertical rod reinforcements in said columns and bent laterally into said concrete floors.

2. A reinforced concrete and masonry structure, the combination of walls built of Z shape structural tile with the cross webs of each unit coinciding with those of units in succeeding courses forming vertical parallel cells in the wall, a niche in the top of said cross webs, horizontal steel rod reinforcements through said niches, and vertical concrete columns cast in said vertical cells, and hollow reinforced concrete floors supported by said walls and columns, said hollow floor a combination of parallel reinforced concrete supporting beams separated by rows of Z shape structural tile forming a series of vertical rectangular cells between beams, and said beams cast integral with said columns, and steel rod reinforcements

extending through the column and bent laterally at right angles to the column and into the said floor beams.

3. A reinforced concrete building construction, the combination of masonry walls built of Z shape structural tile forming continuous vertical parallel cells in the walls, reinforced concrete vertical members or columns cast in certain cells, and hollow reinforced concrete floors supported by said walls, and columns, said hollow floor a combination of parallel reinforced concrete supporting beams separated by rows of Z shape structural tile forming a series of rectangular vertical cells between beams, said cells open at the top and closed at the bottom by a concrete slab reinforced with metal mesh and cast integral with the concrete beams, steel rod reinforcements extending vertically through said columns and bent laterally into the floor rib adjacent to the column.
4. A reinforced concrete building construction, the combination of masonry walls built of Z shape structural tile forming continuous vertical parallel cells in the walls, reinforced concrete vertical members cast in certain cells, and hollow reinforced concrete floors supported by said walls and columns, said hollow floor a combination of parallel reinforced concrete supporting beams separated by rows of Z shape structural tile forming a series of rectangular

vertical cells between beams, a niche in the bottom of the cross web portion of said floor tile forming a passage between said cells, and a concrete slab over and under said rows and beams and cast integral with said beams, metal reinforcements in said slabs, horizontal reinforcements in said beams, vertical reinforcements in said vertical columns and bent laterally into said concrete floor.

5. A reinforced concrete building construction, the combination of masonry walls built of Z shape structural tile forming continuous vertical parallel cells in the wall, reinforced concrete vertical members or columns cast in certain cells, and hollow reinforced concrete floors supported by said walls or columns, said hollow floor, consisting of parallel reinforced concrete supporting beams and rows of Z shape structural tile, forming a series of rectangular vertical cells between beams, said cells closed at the top and at the bottom by concrete slabs reinforced with metal mesh and cast integral with the concrete beams, steel rod reinforcements extending vertically through said columns and bent laterally into the floor ribs adjacent to the columns.
